PRINTING PAD

Bernard Dwofsky, New York, N. Y.

Application June 28, 1934, Serial No. 732,766

4 Claims. (Cl. 91—54.5)

This invention relates to printing pads, and has for its object to provide a pad which will always maintain the inking surface in good condition to enable the rubber stamps to be applied thereto to be moistened with the ink.

More particularly, the object of the invention is to provide an automatic cooperation between the pressure of the rubber stamp applied to the inking surface and the supply of ink or the like to that surface. For this purpose, my invention consists of a casing, an inking surface arranged on the upper part of the casing, and automatically compressible means supplying the inking surface with ink.

The invention consists further in a casing in which there is arranged a flexible reservoir having openings disposed toward the inking surface, and a spring means pressing the flexible reservoir towards the said openings, whereby on the pressure applied to the inking surface, the reservoir is compressed and supplies the inking surface with the necessary ink.

The invention will be more fully described hereinafter and the embodiment thereof shown in the drawing, and the invention will be finally pointed out in the claims.

In the accompanying drawing,

Figure 1 is a plan view partly in section of the improvements in the inking pad forming this invention.

Figure 2 is a section taken on line 2—2 of Figure 1; and

Figure 3 is a similar section, but with the reservoir almost completely collapsed showing the contents of the reservoir substantially used up.

Similar characters of reference indicate corresponding parts throughout the various views.

Referring to the drawing, and more particularly to Figures 1 and 2, a casing 10 of metallic character and substantially of rectangular shape, although any other shape may be utilized, is provided with a cover 11, hinged at 12, as is well known.

Within the casing 10 is an interior metallic container 13 which has an angular portion 14 arranged horizontally at its upper end, and has connected therewith at its lower end a plate 15. Exterior to the member 13, and within the casing 10, is a material suitable for forming a pad, as cloth or the like, indicated at 16, and this extends over the entire top surface of the device, and has its free ends 17 disposed between the bottom of the casing 10 and the plate 15, a clamp therebetween. Below the top surface of the pad material 16, are arranged a suitable number

of pieces of material, as felt or the like, such as are well known in the use of forming inking pads of this character, and these layers are indicated at 19. Disposed below these layers of pad material 19, and blotters 19a is a metallic plate 20 having a large number of small openings 21 therein, and the end portions 22 of this plate rest upon bent-over portions 24 of a reservoir 25, formed of rubber or other suitable yielding material. The reservoir 25 has a rectangular shape 10 and cross section as shown in Fig. 2, and has a width substantially equal to the width of the casing, and a length substantially equal to the length of the casing. This reservoir is filled with a paste consisting of ink ingredients, and some 15 suitable carrier, and this material within the reservoir 25 is capable of exuding out of the openings 21, and serves to wet the pad layers 19 and the inking surface 16.

Below the flexible reservoir 25 is placed a stiff 20 plate 27, below which, in turn, is arranged a helical spring 28. One end portion of this spring exerts its pressure against the plate 27 and the other portion exerts its pressure against the plate 15. Thus, by the action of this spring, the plate 23 27 is continually forced upwardly and the resistance to the action of the spring is the contents of the yieldable reservoir.

The operation of the device is as follows: 30 When a rubber stamp such as is well known is applied to the inking surface 16 with a suitable pressure to ink the surface of the rubber stamp, the inking surface 16 with its pads 19 are pressed downwardly. By such a pressure, the perforated plate 20 moves downwardly to a certain extent and thereby the inking material within the reservoir 25 passes out of the openings 21 and into the felt 19 on the inking surface 16. This is repeated, and in order to make up for the amount of material which passes out of these openings 21, the action of the spring 28 serves to constantly press the bottom of the reservoir 25 upwardly, whereby a constant resistance is supplied to any pressure of the rubber stamp applied to the inking surface. 40

My invention has a special advantage that it always supplies a wet inking surface to the rubber stamp to be applied thereto, and one or two thrusts of the rubber stamp upon the inking surface 16 serve to wet it and place it in good condition for further use. The embodiment described may be made in any shape. The container can be either metal or of other suitable material. The reservoir 25 may be of rubber or 50 any other suitable yieldable material. The in- 55

vention may be very simply manufactured and assembled and made at a relatively small price, and serves to provide an inking pad which has a relatively long life.

5 Upon the contents of the reservoir being used up, a new reservoir can be supplied or the flexible reservoir can be refilled.

I have described my invention as embodied in a certain form, but changes may be made therein 10 without departing from the spirit of my invention as defined by the accompanying claims.

I claim:—

1. An inking pad comprising a casing, an inking surface thereon, an ink paste in the casing, 15 and yieldable means supplying the inking surface with ink.

2. An inking pad comprising a casing, an inking surface thereon, a perforated plate, a flexible reservoir having an open side communicating 20 with the perforations of the plate, and spring means pressing the bottom of the reservoir towards said perforated plate.

3. An inking pad comprising a casing, an inking surface thereon, a perforated plate, a yielding plate below the inking surface, pad material interposed between the inking surface and the perforated plate, a flexible ink-containing reservoir having an open side communicating with the perforations of said plate, a plate on the closed side of the reservoir, and a spring disposed between said plate and the bottom of the casing, 5 said spring exerting a pressure upon the flexible reservoir, whereby upon pressure being applied to the inking surface, the contents of the flexible reservoir are forced against the inking surface.

4. An inking pad comprising in combination, a 10 casing, an inking surface thereon, a perforated plate, a flexible reservoir having an open side communicating with the perforations of the plate, an ink paste in the reservoir, and spring means 15 pressing the bottom of the reservoir towards said perforated plate.

BERNARD DWOF SKY.
